(57) **CLAIM**

The ornamental design for the shoe, as shown and described.

DESCRIPTION

FIG. 1 is a front perspective view of a shoe in accordance with the new design;

FIG. 2 is a top view thereof;

FIG. 3 is a front view thereof;

FIG. 4 is a right side view thereof; and,

FIG. 5 is a left side view thereof.

The broken line showing of the parts of a shoe in FIGS. 1-5 form no part of the claimed design.

1 Claim, 3 Drawing Sheets
